R. V. BLAKE,
POCKET ATTACHMENT FOR HOLDERS, &c.
APPLICATION FILED FEB. 28, 1917.

1,234,859.

Patented July 31, 1917.

UNITED STATES PATENT OFFICE.

RALPH V. BLAKE, OF NEW YORK, N. Y.

POCKET ATTACHMENT FOR HOLDERS, &c.

1,234,859.

Specification of Letters Patent. Patented July 31, 1917.

Application filed February 28, 1917. Serial No. 151,486.

To all whom it may concern:

Be it known that I, RALPH V. BLAKE, a citizen of the United States of America, residing at New York city, county and State of New York, have invented a new and useful Pocket Attachment for Holders, &c., of which the following is a specification.

My invention relates to what may be termed a supplementary pocket for carrying tickets, such as commutation tickets, passes and street car and subway tickets.

The main object is to provide a simple and convenient means for carrying such objects. Another object is to provide such a construction which can be readily attached to the inside pocket of any coat and be readily accessible and yet unobtrusive.

Figure 1 is a perspective view illustrating the use of one form of construction embodying my invention.

Fig. 2 is a vertical sectional view of the same.

Fig. 3 is a view showing the blank from which the main part of the device is made but on a somewhat smaller scale.

Fig. 4 is a detail view of the attaching member.

Fig. 5 is a front view of a modified form of construction embodying my invention.

Fig. 6 is a vertical sectional view of the same.

Fig. 7 is a detail view of a locking device.

Fig. 8 shows a blank for another form of device having one pocket.

Fig. 9 is a horizontal sectional view of the device formed from the blank of Fig. 8.

From the drawings the invention will be seen to comprise a device having one or more pockets, in one case three, together with means for readily attaching the device to the cloth of the wearer's coat.

In the form shown in Figs. 1, 2 and 3, the pocket portion of the device is formed of a blank of suitable material, such for instance, as celluloid. The part 10 forms the back of the device and the two flaps 11 and 12 form the front. The flap 13 is folded between the back and the front and forms an intermediate wall which constitutes the front of the main rear pocket 14 and the back of the two front pockets 15 and 16. The two flaps 11 and 12 may be secured together by means of an eyelet, staple or other suitable device 17, inserted through holes 17'. The flaps 18 and 19 are bent upward at the rear so as to close the pockets at the bottom.

The device is secured to the fabric by means of the member shown in Fig. 4, which consists of a strip of metal or wire 20 secured at 21 to a flap 10' at the top and provided at its lower front end with a button 22 which projects through the hole 23 at the rear of the back 10. The rear end of the strip 20 is provided with an opening 24 somewhat larger than the head of the button 22. The device is put in use by inserting the rear member of the strip 20 into the pocket or other horizontal opening in the coat, vest or other wearing apparel. The rear end of the strip is then forced forward so as to push the head of the button 22 into the fabric and through the opening 24. The locking piece 25 is then pushed over the fabric and the head of the button 22, and turned so as to lock the parts in place. This holds the parts securely so that the attachment cannot become disengaged accidentally.

The strip 20 may be provided with a number of projections such as 26 to increase the grip or friction upon the ticket or other article inserted in the pocket 14.

In the form shown in Figs. 5 and 6, two pieces of celluloid are required, one piece has a portion forming the back 30 with the rear flap 31, intermediate flap 32, and the two side flaps 33. The other piece forms the front 34 and the two rear flaps 35. The two side flaps 33 are secured to the front, for instance, by means of an eyelet 36. This particular form has two pockets, one in front of the other. In this form the fastening device consists of a button 37 projecting forwardly from the rear member 38 and acting in conjunction with a tab 39 having the opening 40.

In the form shown in Figs. 8 and 9 one piece of celluloid is employed which is so shaped as to form a single pocket. In this case the part 41 constitutes the back, 42 is the rearwardly and downwardly extending flap, 43 is the front, and 44-44 are side flaps which are bent to the rear and inserted through slots in the base plate 45 which carries a button 46 projecting to the rear. A resilient strip 47 constitutes the member 105 which fits in the pocket and is provided with a T-shaped slot 48. The head of the button 46 is adapted to be inserted in the broad portion of the slot 48 when the strip 47 is drawn downward. By allowing the strip 47 to come back to its normal position of rest the narrow portion of the slot 48 draws

the fabric up around the shank of the button 46, and holds this part in position without the use of any additional locking member.

5 From the foregoing it will be seen that the device may be made in a number of different ways and may be readily attached and detached to any pocket or to any horizontal member.

10 It will be obvious that the particular use of the device is not material to the broader aspect of my invention, but that the holder may be employed for other articles than tickets, and that the shape of the pockets will be varied to correspond with the shape or size of the article which it is desired to carry. It will also be obvious that the invention is adapted to devices for carrying 15 cigars, cigarettes, matches, pencils, and the like.

20 I claim:

1. An attachment for pockets and the like comprising a ticket receptacle member, a downwardly extending member connected to the top of said receptacle member, one of said members having an opening, a button carried by the other member adapted to force fabric through said opening and a catch coöoperating with said button for the 25 purpose specified.

30 2. In an attachment of the character described, the combination of a receptacle member and an attachment member connected at the upper portion thereof and extending downward at the rear, one of said 35 members having an opening and the other

member having a projecting button adapted to hold the fabric in said opening.

3. In an attachment of the character described, the combination of a receptacle 40 member having a rearwardly and downwardly turned top flange adapted to rest on the edge of a pocket, and means for securing the lower end thereof to the back of said receptacle member with the fabric of the 45 pocket interposed.

4. In an attachment of the character described, the combination of a celluloid receptacle member having integral flaps forming pockets, and a downwardly and rearwardly turned flap at the upper end, and means for securing the lower end of said latter flap to the back of the receptacle member with the 50 fabric interposed.

5. In an attachment of the character described, the combination of a receptacle member, a button secured thereto and projecting to the rear thereof, an attachment member connected to the upper edge of said receptacle member and having an opening 55 adapted to receive said button for the purpose specified.

6. In a device of the character described, a receptacle member and a fastening member having a resilient arm, one of said members having a headed button and the other member having an opening adapted to receive the head of said button, said parts being so arranged that when in the normal position of rest said resilient arm will cause 70 fabric to be gripped over said button head.

RALPH V. BLAKE.

Copies of this patent may be obtained for five cents each, by addressing the "Commissioner of Patents, Washington, D. C."
